(57) **CLAIM**

I claim the ornamental design for a wire termination blade, as shown.

DESCRIPTION

1. FIG. 1 is a perspective view of the wire termination blade, looking towards the top and left sides;
2. FIG. 2 is an elevational view of the left side;
3. FIG. 3 is an elevational view of the right side;
4. FIG. 4 is a top plan view;
5. FIG. 5 is a bottom plan view;
6. FIG. 6 is an elevational view of the front end; and,
7. FIG. 7 is an elevational view of the back end.
